UNITED STATES PATENT OFFICE.

LEES RAY, OF WAVERTREE, ENGLAND.

DESIGN FOR A NOSE-CLAMP.

SPECIFICATION forming part of Design No. 27,424, dated July 27, 1897.

Application filed February 17, 1897. Serial No. 623,881. Term of patent 14 years. Patented in England October 29, 1895, No. 20,358; in France April 28, 1896, No. 255,907, and in Germany December 9, 1896, No. 67,992.

To all whom it may concern:

Be it known that I, LEES RAY, a subject of the Queen of Great Britain and Ireland, and a resident of Wavertree, near Liverpool, England, have invented a certain new and original Design for a Nose-Clamp, (for which I have obtained patents in Great Britain, bearing date October 29, 1895, No. 20,358; in France, bearing date April 28, 1896, No. 255,907, and in Germany, [Gebrauchsmusterschutz,] bearing date December 9, 1896, No. 67,992,) of which the following is a specification.

My design is shown in the accompanying drawings, in which—

Figure 1 is a perspective view of my design, and Fig. 2 a side view.

The plates A A' have each a plain portion X and a curved portion Y. On the portion X are perforated bosses a. The lower edges of the plates have recesses b, while the rear edges have recesses d and f, with an intermediate prominence e, and the rear and lower edges end in rearwardly-projecting flared portions c.

I claim—

The design for a nose-clamp, as herein described and shown.

In witness whereof I have hereunto set my hand in presence of two witnesses.

LEES RAY.

Witnesses.

CHAS. ROCHE,
JOHN HARVEY.
